SALTS OF NITROFORM WITH HYDRAZINES
 James R. Thornton, Tamaqua, Pa., assignor to Atlas
 Chemical Industries, Inc., Wilmington, Del., a corpora-
 tion of Delaware
 No Drawing. Filed Dec. 26, 1963, Ser. No. 333,662
 3 Claims. (Cl. 260—501)

The present invention relates to salts of nitroform and more specifically, to salts of nitroform with hydrazine and substituted hydrazines. Further the present invention relates to a method of producing such salts.

Nitroform, trinitromethane, having a plurality of nitro groups with a single carbon and a single hydrogen atom would at first glance be thought to be a useful explosive or explosive component. However, the usefulness of nitroform is severely curtailed because it is highly acidic and has a low decomposition point, about 30° C. Nitroform has a very penetrating and unpleasant odor. Although it appears attractive on paper, the physical disadvantages of nitroform have substantially eliminated it from use in the explosives or propellant art. Mixtures of nitroform with other materials, such as amines or ammonia to form complexes have not found favor in the art as the stability of such complexes show little or no improvement over the stability of nitroform alone.

The present invention provides a nitroform salt which is stable over a long period of time and at temperatures substantially above the decomposition temperature of nitroform. The present nitroform salts have little or no odor and exhibit inhibited acidity. The present salts are highly inflammable but do not appear to be detonatable under ordinary circumstances. The salts are useful to sensitize ammonium nitrate and may aptly be used in propellant compositions and systems.

In accord with the present invention, a nitroform salt is provided which consists of nitroform and a member of the group consisting of hydrazine, monoalkyl hydrazines, such as methylhydrazine, and ethylhydrazine; monoarylhydrazines, such as 2,4-dinitrophenylhydrazine, phenylhydrazine, 2,5-dichlorophenylhydrazine, 1-naphthylhydrazine, p-nitrophenylhydrazine, p-bromophenylhydrazine, 2,4,6-trinitro-phenylhydrazine, and 2,4,6-trichlorophenylhydrazine; alkylaryl hydrazines, such as, 1-methyl-1-phenylhydrazine; unsymmetrical dialkylhydrazines, such as 1,1-dimethylhydrazine, and; unsymmetrical diarylhydrazines, such as 1,1-diphenylhydrazine, and 1-benzyl-1-phenylhydrazine.

The salts of the present invention may be prepared by initially dissolving the nitroform component in a short chain alcohol and then slowly adding hydrazine or a hydrazine derivative to precipitate the nitroform salt. Alcohols containing from 2 to 6 carbon atoms are particularly adapted to use in the present invention, for example, ethyl, methyl, propyl, isopropyl, and butyl alcohols. The nitroform-hydrazine salt or the nitroform-hydrazine derivative salt product may be recovered by separating it from the supernatant alcohol by filtration. If desired the product may be recrystallized from a short chain alcohol solution. The salt products of the present invention are substantially odorless and are stable over a long period of time, generally over a period of 6 months and at temperatures ranging from 18° to 100° C.

The following examples are illustrative of the process of producing the present nitroform salts:

2

Example 1

151 grams of nitroform (1 mole) was dissolved in 1000 cc. of iso-propylalcohol. Hydrazine was then added to the solution in a dropwise manner. A precipitate formed. Additional hydrazine was added until precipitation was complete. The precipitate was separated by filtration and dried. The dried product was then recrystallized from a matrix of iso-propyl alcohol. 91 grams of product, nitroform-hydrazine salt, was recovered representing a yield of 50%. The salt product had a melting range of 121 to 123° C. with some decomposition starting in the melting range. The total nitrogen content, determined by the micro Dumas procedure, was found to be 38.2% by weight of product. The calculated nitrogen content for the nitroform-hydrazine salt product was 38.0%. The salt product was found to be quite odorless and stable over a period of 18 months at temperatures ranging from 18 to 100° C.

Example 2

Nitroform and 2,4-dinitrophenylhydrazine was reacted by the method of Example 1. The melting range of the product was found to be 120° C. to 123° C. The total nitrogen content was found to be 23.17% by weight of the product. The calculated nitrogen content for the nitroform-2,4-dinitrophenylhydrazine salt product was 28.09%. Again the salt product was found to be quite odorless and stable over a period of 18 months at temperatures ranging from 18° to 100° C.

Other salts of substituted hydrazines and nitroform may be prepared in a manner similar to the method described in Example 2, for example, nitroform may be reacted with any of the following: 1-methyl-1-phenylhydrazine, 1,1-dimethylhydrazine and 1,1-diphenylhydrazine, to produce nitroform salts.

What is claimed is:

1. A salt of nitroform and a member of the group consisting of hydrazine, 2,4-dinitrophenylhydrazine, phenylhydrazine, p-bromophenylhydrazine, 1-methyl-1-phenylhydrazine, p-nitrophenylhydrazine, 1,1-diphenylhydrazine, 1-benzyl-1-phenylhydrazine, 1-naphthylhydrazine, methylhydrazine, ethylhydrazine, 2,5-dichlorophenylhydrazine, 2,4,6-trichlorophenylhydrazine, 1,1-dimethylhydrazine, 2,4,6-trinitrophenylhydrazine.
2. A salt of nitroform and hydrazine.
3. A salt of nitroform and 2,4-dinitrophenylhydrazine.
